IGNITION WIRE BOOT

Richard P. Dugger, South Bend, Ind., assignor to
Ristance Wire, Inc., Bremen, Ind.

Filed Jan. 6, 1975, Ser. No. 538,926

Term of patent 14 years

Int. Cl. D13—03

U.S. Cl. D26—1 A

FIG. 1 is a perspective view of an ignition wire boot embodying the present design;

FIG. 2 is a perspective view of the side of the ignition wire boot opposite that shown in FIG. 1;

FIG. 3 is a side elevational view of the ignition wire boot;

FIG. 4 is an edge elevational view of the ignition wire boot;

FIG. 5 is an elevational view of the edge opposite that shown in FIG. 4;

FIG. 6 is an end elevational view of the ignition wire boot; and

FIG. 7 is an elevational view of the end opposite that shown in FIG. 6.

I claim:

The ornamental design for an ignition wire boot, substantially as shown.
